SPIRIT STOVE

Ferenc Fischl, Stockholm-Hagersten, Sweden,
assignor to Aktiebolaget Amerika-Matts, Falun,
Sweden, a corporation of Sweden

Application June 23, 1948, Serial No. 34,791

Claims priority, application Sweden
December 12, 1947

3 Claims. (Cl. 126—43)

1

The present invention relates to a heater such as a spirit stove comprising a container enclosing a substance for absorbing fuel and having gas escaping holes and an opening at its top for filling the container with fuel. In spirit stoves of this kind the fuel is gasified within the container. The gas escapes through the aforementioned holes or apertures and the heat produced by the burning gas heats the container so as to cause a continuous development of gas. Similar stoves operate satisfactorily only under specific conditions, compelling the user to exactly follow operating instructions to produce a good result. Particularly the problem of lighting the stove without special manipulations immediately after filling up with fuel has proven to be difficult. With earlier designs it was necessary to pour off surplus fuel, which could not be controlled from outside and, moreover, it was often necessary to repeatedly pre-heat the burner to effect ignition.

It is the main object of the present invention to eliminate the said difficulties by providing means ensuring safe operation of the heater without particular measures of precaution. A further object of the invention is to provide means rendering the pre-heating of the apparatus more effective so as to ensure its ignition with a single pre-heating operation, even if the apparatus had just been filled with fuel.

Further objects and advantages of the invention will be apparent from the following description considered in connection with the accompanying drawings in which:

Fig. 1 is a side-elevation, partly in section, of a spirit stove according to the invention.

Fig. 2 is a top view of the stove, part of a support for a cooking vessel being omitted in the lower half of the figure.

Fig. 3 shows a stopper for the filling aperture of the stove.

Fig. 4 is a side-elevation, partly in section, of a spirit stove for two flames.

Fig. 5 is a top-view of a ring of dry spirit, and Fig. 6 is a sectional view thereof.

Fig. 7 is a partly sectioned side-elevation of a container for a charge cartridge for the spirit stove.

Fig. 8 is a vertical section through a spirit stove provided with an insertable distributor element.

Fig. 9 is a horizontal section through the distributor element on line IX—IX in Fig. 8.

Like parts are designated by like numerals in all figures of the drawing.

In the drawings, numeral 10 designates a spirit consumed and can be reimpregnated with fuel.

2

stove, which consists of a cylindric container 12, the bottom of which is closed by a screw-lid 14, and which at the top merges in an upper part 16 of cylindric shape and having a smaller diameter than that of the container 12. In the portion connecting the container 12 and the upper part 16 a groove 18 is provided adjacent to the upper part 16. Outside the groove 18 is another groove 19 which is more shallow than the groove 18. The upper part is closed at the top by a cover 28 and provided with a hollow rim forming a pocket 20 having a bottom 22 formed by a cone-shaped or downwards convex hollow filter or screw element 24, located in the interior of the upper part 16 and with its top turned downwards. In the embodiments illustrated, the element 24 acts as a filter, because its walls are provided with small holes 26. The pocket 20 is adapted to be closed by means of a threaded stopper 28 which may be tubular and communicating with the interior of the container through a plurality of holes 30. On a level somewhat above the bottom 22 the outer side wall of the upper part 16 has small holes 31 which are placed in the rim portion 17 connecting the side wall with the horizontal top (Fig. 8). The container 12 is filled with a liquid absorbing substance 32, such as cotton, wad, textile, fossil dust etc. The material may consist, as is indicated in Fig. 1, of a coherent renewable unit of approximately the same shape as the container 12 and may be procured from burnt fossil dust. The stopper 28 is provided with means for carrying a supporting plate 34 for a cooking vessel not shown.

Fig. 4 shows two stoves of the same construction as shown in Fig. 1, but built on a common container 36 filled with the absorbing material 32 to the level of the conic element 24. Figs. 5 and 6 show a ring-shaped combustible body 37, for instance of dry spirit, so dimensioned that it fits into the groove 18. Fig. 7 shows a storage container 38 closed at the bottom by means of a screw-lid 40 and intended for preservation and transportation of a cartridge 32 impregnated with fuel and being of the shape and kind as described with reference to Fig. 1. The advantage of this arrangement is evident, since no liquid combustible need be carried in the spirit stove for example on an excursion. The cartridges might be impregnated with the combustible before the departure and be put into their containers, thus avoiding any risk of liquid combustible flowing out and destroying other equipment. The cartridges themselves are not consumed and can be reimpregnated with fuel.

In the embodiment shown in Figs. 8 and 9 the spirit stove is provided with an attachable distributor element of cylindrical cross-section, the upper edge of the casing 44 of which is secured to the outer edge of the bottom surface of the filter 23', 24'. The casing 44 is preferably made of thin sheet-plate and is completely or partly longitudinally slotted, so that its upper portion is resiliently pressed against the inside wall of the upper part 16. The casing 44 is open at the top and closed at the bottom by a downwards bulging bottom piece 48 fastened to the lower edge of the casing 44. Both, the casing 44 and the bottom 46, are perforated over their entire surface, preferably with considerably smaller holes than the openings and holes of the filter element 23, 24 in the upper part 16. In the embodiment shown, the container 42 is filled with glass wool.

When using the spirit stoves shown in Figs. 1-7 the stopper 28 is screwed off. Fuel is poured into the pocket 20 and flows through the perforations 26 in the element 24 down into the liquid absorbing material 32. An allotted amount of combustible will be completely absorbed by the material. If no fuel measuring devices are available, the fuel may be filled in until it reaches the bottom 22 of the cone-shaped element, without causing any difficulties for the subsequent lighting of the stove. It can be conveniently ascertained from the outside that the quantity of the fuel filled in is not so great as to disturb the operation of the stove. When the stove has been filled in this manner, the stopper 28 is screwed on, and fuel is poured, or a ring of for instance dry spirit is placed into the groove 18 and ignited. Hereby the wall of the upper section is heated up, and the heat is transferred mostly through conduction in the material, but also through radiation to the container, whereby development of gas from the fuel absorbed in the absorbing material begins to be effected. The gas developed is collected in the space above the absorbing material, and, after enough gas has accumulated, the gas escapes through the holes 31, where it is ignited by the preheating flame. The gas emerging from apertures 31 burns in flames extending substantially centrifugally. The size of the gas-collecting space above the absorbent mass is of decisive importance for the correct functioning of the stove or apparatus, the cone-shaped element 24 assuring the correct volume of the space under all circumstances.

When using the spirit stove shown in Figs. 8 and 9, spirit is filled into the pocket 20' and flows through the holes in the filter element 23', 24' into the element 43. As the latter extends deeply into the mass with which the container 42 is filled, the spirit is quickly absorbed by the absorbent mass via the perforated walls of the element 43. A relatively small part of the spirit remains in the material contained in casing 44. Thereupon the groove 18' is filled with spirit and ignited. Hereby the wall of the upper part 16' is heated up and produces a surprisingly quick development of gas in the impregnated mass of the container 42 due to heat conduction through the element 43 and its wall 44. Whereas the time until a sufficient amount of gas has been produced and accumulated in the upper part 16' and begins to escape through the holes 31 where it is ignited by the flame of the spirit burning in the groove 18', amounts to a few minutes, only a fraction of that period elapses between the ignition of the pre-heating spirit in the groove 18' and the escape of the gas out of the container 42

and the ignition of the gas, if the stove is provided with the distributor element 43. A further essential advantage of this embodiment is obtained by the conduction of heat through the casing wall 44 of the element 43, assuring a quick production of gas from the lower layer of the absorbent mass in container 42 even if the spirit in the upper layer of the spirit absorbing mass has already been consumed. This advantage is particularly obvious, when the spirit absorbing mass in the container 42 does not consist of a coherent material, but of a powder impregnated with spirit. Such powder may be simply filled into the container 42, for instance from a reservoir of supply containing such spirit-impregnated powder, after the stove has been turned upside down, and the detachable bottom for the container 42 has been screwed off.

While several more or less specific embodiments of my invention have been shown, it is to be understood that this is for purpose of illustration only, and my invention is not to be limited thereby, but its scope is to be determined by the appended claims viewed in the light of the prior art.

What I claim is:

1. A spirit stove comprising, in combination, a container having a lower part of relatively large cross-section and a cylindrical upper part of relatively small cross-section; said container having at the junction between said upper part and said lower part an annular groove for receiving alcohol for pre-heating the stove; said upper part having an opening for pouring alcohol into the container and having an annular hollow rim portion having an open bottom and an inner wall surrounding said opening; a cover fitting into said rim portion adjacent to its inner wall for closing said opening when the stove is in normal operation; a fluid-pervious screen member forming a vapor chamber, disposed in said upper part and separating the interior of said rim portion and the space surrounded thereby from said container; spirit-absorbing means disposed in said lower part; said rim portion having an outer wall; and a plurality of apertures in said outer wall for discharging spirit vapor in a radially outward direction.

2. A spirit stove comprising, in combination, a container having a lower part of relatively large cross-section and an upper part of relatively small cross-section; said upper part having an opening for pouring alcohol into the container and a hollow rim portion having an open bottom and an inner wall surrounding said opening; a cover fitting into said rim portion adjacent to its inner wall for closing said opening when the stove is in normal operation; a fluid-pervious screen member forming a vapor chamber, disposed in said upper part and separating the interior of said rim portion and the space surrounded thereby from said container; spirit-absorbing means disposed in said lower part; said rim portion having an outer wall; and a plurality of apertures in said outer wall for discharging spirit vapor in a radially outward direction; said screen member comprising a substantially horizontal, plane and uninterrupted portion abutting the inside of said upper part beneath said rim portion and a substantially concave portion extending downward from said horizontal portion for resisting expansion of said absorbing means into said upper part and maintaining the desired size of said vapor chamber.

3. A spirit stove comprising, in combination, a

container having a lower part of relatively large cross-section and an upper part of relatively small cross-section; said upper part having an opening for pouring alcohol into the container and a hollow rim portion having an open bottom and an inner wall surrounding said opening; a cover fitting into said rim portion adjacent to its inner wall for closing said opening when the stove is in normal operation; a fluid-pervious screen member forming a vapor chamber, disposed in said upper part and separating the interior of said rim portion and the space surrounded thereby from said container; spirit-absorbing means disposed in said lower part; said rim portion having an outer wall; and a plurality of apertures in said outer wall for discharging spirit vapor in a radially outward direction; said screen member forming a receptacle inserted in said upper part and extending into the lower part and having a substantially horizontal, plane top surface closing the bottom of said rim portion and said upper part at the level of said bottom, a fluid-pervious screen partition dividing said

receptacle into an upper chamber, forming said vapor chamber, and a lower chamber, and spirit absorbent matter disposed in said lower chamber.
